CLAIM

CPC G07F 17/3213; G07F 17/3288; G07F

The ornamental design for a display screen with graphical user interface of a roulette game, as shown and described.

17/3209; G07F 17/3262; G07F 17/323;

DESCRIPTION

G06F 3/048; G06F 3/0481; G06F

The FIGURE is a front view of a display screen with graphical user interface of a roulette game showing our new design.

3/04812; G06F 3/04815; G06F 3/04817;

The peripheral broken line represents a boundary of the display screen and forms no part of the claimed design. The
